Des. no. 20,191

UNITED STATES PATENT OFFICE.

HENRY CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,191, dated October 7, 1890.

Application filed September 8, 1890. Serial No. 364,352. Term of patent 3½ years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said State and county, have invented and produced a new and original Design for Heating-Stoves, of which the following is a specification, reference being had to the accompanying drawing, forming a part thereof and consisting of a single figure, affording a view in perspective of our newly-designed stove.

15 The leading feature of our design consists in the ornamentation of the various parts.

Rising from the plain base A is the fire-box A', separated from the superimposed combustion-chamber A² by the plain horizontally-projecting flange A³.

20 The combustion-chamber is provided with a corner-column A⁸, composed of a series of short parallel diagonal ribs, and on its front side with a door A⁹, and on its upper end 25 with a plain horizontally-projecting flange A⁴, surmounted by a dome A⁵.

The upper ends of the legs A⁶ are each provided on their outer surface with a central acanthus-leaf ornament B, and on opposite 30 sides of such ornament with a series of ribs B', the individual ribs extending downwardly and outwardly from the leaf ornament to the edge of the leg, the ribs in each series gradually diminishing in length from the top of the 35 leg downward.

The middle portion of each leg is provided with a foliated ornament B² and the lower end with a series of horizontal ribs B³.

40 The front side of the fire-box is provided with a door B⁴ and ornamented by a series of corner-columns B⁵, each column being composed of a vertical row of short horizontal ribs.

45 The lower part of the door is provided with a series of vertically-elongated draft-openings B⁶, alternating with foliated ornaments, and a lower border beneath the openings composed of a series of horizontal ribs B⁷, one above the other.

The upper part of the door is provided with 50 a central anthemion ornament B⁸ and a lower wave-line B⁹, extending lengthwise of the door, having scroll terminals and scroll branches extending upward on opposite sides of the central ornament, and honeysuckle ornaments B¹⁰ at the ends of the door.

One end of the stove is provided with a door C, the upper portion of which is located on the lower portion of the combustion-chamber and the lower part of the door upon the 60 upper part of the fire-box.

The vertical and upper edges of the door are provided with a beaded border C' and the body-surface of the door with central foliated ornaments C² and corner-scrolls C³.

Beneath the door C is the plain horizontally-projecting shelf C⁴.

65 What we claim as new is—

1. The ornamental design for a heating-stove, herein shown and described, consisting 70 of a plain base, a fire-box rising from the base, having corner-columns severally composed of a series of short horizontal ribs and on its front side a door having draft-openings and foliated ornaments, a combustion-chamber 75 above the fire-box, having a corner-column composed of a series of short parallel diagonal ribs, a door on the front side and a plain horizontally-projecting top flange, a plain horizontally-projecting flange between the fire-box and combustion-chamber, a door on one end of the stove overlapping the fire-box and combustion-chamber, having foliated ornaments thereon, and a plain horizontally-projecting shelf on the end of the stove directly 85 beneath the end door.

2. In a design for a heating-stove, the ornamental design on a stove-door, herein shown and described, consisting of a horizontal row of vertically-elongated draft-openings 90 alternating with foliated ornaments on the lower part, with a lower edge border beneath the openings, composed of a series of horizontal ribs, one above the other, and on the upper part of the door a central anthemion ornament, and a wave-line extending lengthwise 95 of the door beneath the central ornament, having scroll terminals and scroll branches

OVER

extending upward on opposite sides of the central ornament, with a honeysuckle ornament at each end of the door.

3. In a design for a heating-stove, the ornamental design on the legs, herein shown and described, consisting of an acanthus-leaf ornament centrally located on the outer surface of the upper end of the leg, a series of ribs on both sides of such ornament, the individual ribs extending downwardly and outwardly from the leaf ornament to the edge of the leg, the ribs in each series gradually diminishing

in length from the top of the leg downward, a foliated ornament on the middle part of the leg, and on the lower end of the leg a series 15 of short horizontal ribs.

In testimony whereof we have hereunto set our hands this 6th day of September, 1890.

H. CLAY BASCOM.
FRANCIS RITCHIE.
